10 Claims. (Cl. 264—3)

1

This invention pertains to controls for aircraft, and more particularly to apparatus for controlling the pitch of propellers.

A particular object of the invention is the provision of an attachment in the nature of a solenoid operated or controlled hydraulic governor head adaptable to certain standard pitch-controlling governors to replace manual and motor-driven controls heretofore in general use on aircraft for changing the pitch of the propeller blades while in flight, or operation.

In accordance with present practices on so-called standard propellers, built-in piston and cylinder means in the propeller hub are actuated hydraulically, under control of a self-contained engine driven governor including a pilot valve for controlling oil flow to and from the hydraulic means, for the purpose of altering the pitch of the propeller blades.

Said pilot valve in the governor, in turn, is controlled by a fly-weight type of governor balanced by a single spring known as a speeder spring; by changing the tension of this speeder spring the pilot valve is actuated variously to effect the pitch-changing function of the governor.

Various means have been employed heretofore for enabling the pilot to control the tension of the speeder spring remotely from the cockpit, it being understood that these governors are mounted immediately behind the propeller; these prior control arrangements have included cable-actuated rack and gear means as well as electric motor means in various modifications, all of which are subject to serious objections particularly in high-altitude operation, and all of which are relatively more bulky or complex, or both, than the governor head of the present invention.

The more detailed objects of the present invention include the provision of a governor control means or head which is more reliable under severe flight conditions; which is of simple, rugged, compact and light-weight construction; which is readily adaptable to standard propeller installations and practices; which uses the engine oil at engine pressures as the hydraulic actuating medium for varying tension on the speeder spring; which employs a novel, simplified solenoid valve means electrically controlled from the cockpit for selectively regulating the flow of engine oil relative to the hydraulic tensioning means for the speeder spring; which provides a simplified limit signalling means back to the cockpit to indicate the limit setting of pitch; which provides a simple adapter means for shunting off oil from the

2

engine line ahead of the governor for use in the novel control unit or head; which provides a novel hydraulic locking means as part of the hydraulic tensioning means for the speeder spring so that any setting of the latter will be positively maintained, so far as the control exercised by the governor head is concerned; and which affords a device having the foregoing objects and advantages and which is at the same time less costly to make and maintain than electric governor controls.

Additional objects, advantages, and aspects of novelty of the invention relate to details of construction and operation of the illustrative embodiment described in view of the annexed drawings in which:

Fig. 1 is a perspective view of a propeller governor head and the novel solenoid operated control head mounted thereon;

Fig. 2 is a top plan view, to enlarged scale, of the device of Fig. 1;

Fig. 3 is a vertical section through the control head and part of the governor head, taken along lines 3—3 of Fig. 2;

Fig. 4 is a horizontal section, taken along lines 4—4 of Fig. 3;

Fig. 5 is a horizontal section, taken along lines 5—5 of Fig. 3;

Fig. 6 is a fragmentary vertical section through one of the solenoid valve units, taken in the direction of lines 6—6 of Fig. 4;

Fig. 7 is a fragmentary vertical section looking in the direction of lines 7—7 of Fig. 6;

Fig. 8 is an elevation of the oil-line adapter;

Fig. 9 is a circuit diagram;

Fig. 10 is a vertical sectional detail through the switch housing showing the limit switches.

A complete governor head assembly is shown in Fig. 1, and includes a known type of governor unit, generally indicated at 10, surmounted by the novel control head generally indicated at 11; this assembly is mounted on the engine immediately behind the propeller, the governor unit including a base flange 12 provided with bolt holes 13 for this purpose.

While the invention herein disclosed and claimed relates to the control head, and only pertinent parts of the governor, such as the speeder spring are shown in detail, the description is facilitated by pointing out that the governor, includes a gear type of pump (not shown) driven from the engine by either a coupling gear, splined shaft, or the like, situated within the governor head base portion 12; and it is the function of this gear pump to boost the pressure of the en-

gine oil for the purpose of actuating the hydraulic pitch-changing means in the propeller hub, such actuation being under control of a pilot valve (not shown) in the governor head, which is in turn controlled by the speeder spring assembly.

The governor head 10 is provided at its upper end with a seating flange 14 onto which fits the base portion 15 of the control head body casting, the latter being secured thusly by nuts 16 on bolt studs 17 from said body casting.

In Fig. 3, only the uppermost portion of the governor head, and particularly the flange 14 thereof, appears, but it is in this part of the governor that the speeder spring 18 is situated, the bottom part of the spring being seated in a presser disc 19 on a rod 20 reciprocable to actuate the pilot valve (not seen).

Presser disc 19 includes an annular riding portion 21 against which bear the offset lever arms 22 of fly-weights 23, pivoted at 24 on fly-wheel 25 concentric with rod 20 and driven with the pump gear.

From the foregoing description of the speeder spring assembly, it will appear that the fly-weights 23, rotating with fly-wheel 25, are thrust centrifugally outward, causing lever arms 22 to exert an upward lifting effort on the presser disc 19, which is counteracted to varying degree by the speeder spring 18 depending upon the tensioning of the latter under selective control of the pilot or engineer; and it will further appear that once the tension of the speeder spring is set, the control or actuating rod 20 for the pilot valve will be maintained in a certain position, which in effect will correspond to setting and maintenance of the propeller blades at the desired pitch, and rotation of the propellers at the required number of revolutions per minute, hereinafter referred to as R. P. M. It is again pointed out that the aforesaid speeder spring, pilot valve, and associated governor means are known in the art, and that various expediencies have been resorted to heretofore for varying the tension of the speeder spring from the cockpit by remote control means, and that the present invention has for its principal object the provision of an attachment readily adaptable to a known type of governor head of the class hereinabove described, without requiring alteration or machine work upon the latter, to selectively tension the said speeder spring by electrically controlled, hydraulically powered means utilizing oil from the engine, and at engine pressures for the purpose, as will now appear.

Referring to Fig. 3, the control head 11 consists of a body casting having a large chamber 30 in the base part 15 to enclose the speeder spring assembly, which, as heretofore explained, is part of the governor means, there being an extensive vertical piston chamber 31 above said chamber housing certain hydraulic means for tensioning the speeder spring, said hydraulic means including a piston rod 32 having a cup washer 33 screwed into its lower end and in which the upper, reduced, end of the speeder spring 18 is seated.

Piston rod 32 extends upwardly through a sealing ring 34 in a lower cylinder sealing plate or disc 35 provided with a sealing ring 36 about its circumference, said sealing disc 35 fitting against a shoulder 37 in the cylinder or chamber portion so as to be stopped against upward displacement, there being a large stop gasket 38 expanded into a groove in the cylinder chamber on the lower side of this disc whereby the latter is also held against downward displacement, so that in effect

the disc 35 sealingly closes off the bottom of the piston chamber of cylinder 31.

Higher up in the main cylinder is another sealing plate or disc 40 stopped upwardly against a shoulder 41, and downwardly against a stop gasket 42, there being an outer sealing ring 43 for the plate and a small inner sealing ring 44 about piston rod 32, so that in effect the main cylinder chamber is divided into upper and lower sub-chambers or cylinders sealed off from each other, the upper sub-cylinder portions being indicated at A, A', and the lower portions at B, B'.

In sub-cylinder B—B' is a control piston 50 fast on rod 32 against shoulder 51 as held by sprung washer 52, sealing rings 53, 54 preventing passage of liquid around this piston.

Movement of control piston 50 downwardly compresses the speeder spring; movement upwardly relaxes said spring.

In the upper sub-cylinder A—A' is a regulating piston 60 fast on rod 32 against shoulder 61 thereon as held by a sprung washer 62, sealing rings 64 and 65 preventing passage of liquid around this piston from chamber portion A to A' and vice versa, movement of said liquid, however, occurring through a vent 66 from one face of this regulating piston to the other, chamber portions A and A' being filled with a liquid having a viscosity affected as little as possible by temperature changes, and the diameter of the vent passage being selected for a liquid of given viscosity to regulate the speed of upward and downward displacement of the entire piston assembly to a desired average rate between the extremes of temperature encountered in aircraft operation, as otherwise there is an excessive difference in the speed of operation of the device at 160° F. as compared with the response at minus 65° F. for example, if such regulating means is not provided. A filling vent with closure screw 67 is provided at the top of sub-cylinder A for introducing the special viscosity liquid into the regulating piston section.

As seen in Figs. 1 and 3, a cylindrical switch housing 70 is mounted on top of the control head by means of screws 71 in hold-down cleats 72 engaged in groove 73 on the housing.

Interiorly of the switch housing 70, Fig. 10, are a pair of adjusting screws 75 each having reduced studs 76 rotatably seated in the top of the head casting, the upper ends of these screws being flanged as at 77 with their slotted heads 78 projecting freely through the top of the casing 70.

Threaded onto each of the screws 75 is a switch-supporting bracket 79 having a curved side conformable to the inner curvature of the housing 70 such that the brackets may move up and down, but are prevented by interfitting curved portions at 80 from swinging about their respective adjusting screws 75.

Carried on each bracket 79 is a sensitive switch, one of these being the upper limit switch 81, and the other being the lower limit switch 82, and each said switch has an operating button, 83 and 83', the former being pitched oppositely from the latter for engagement by an operating washer 84 carried on the upper extremity of the piston rod 32; thus, when the piston rod moves toward its upper limit of travel, the rounded edge of washer 84 will cam button 83 inwardly to operate switch 81 in a manner to be explained; and when the piston rod moves toward its lower limit of travel, washer 84 will cam button 83' inwardly and operate the corresponding switch 82. The positions of said limit switches 81 and 82 are

determined by rotating the corresponding adjusting screws 75 to raise or lower the same, set screws 85 then being tightened against the stud portions 76 to secure the switches in adjusted position. An elevation of the switch 81 is seen in Fig. 3.

The hydraulic medium for operation of the control piston 50 is oil taken from the aircraft engine and utilized at engine pressures ranging at fairly constant values between 38 and 50 pounds per square inch, the means for deriving this operating oil separately from the higher-pressure propeller oil in the governor head (the pressure of which, however, may at times drop to zero) being a feature of the invention, and comprising an annular metal block (Fig. 8) 90 having bolt holes 91 positioned to pass mounting bolts 92 (Fig. 1) on a part of the governor head known as the cut-out switch and indicated at 93. This cut-out switch is operated under certain conditions not important to the present disclosure, by change in pressure of the engine oil which communicates with the switch structure through an internal passage in switch unit 93 from the well or bore in the governor head casting just above the base flange 12, there being a boss 94 cast on the head to provide a seat for said cut-out switch, and through which boss is a bore (not seen) passing the engine oil into said switch unit 93.

The annular block 90 of Fig. 8 constitutes an adapter which is interposed between the switch unit 93 and the boss 94 and utilizes elongated switch mounting bolts 92 to hold the parts in assembled relation, as in Fig. 1. The annular adapter block 90, Fig. 8, is provided with a central bore 95 through which engine oil passes as aforesaid into the cut-out switch unit 93, said block including an eccentric bore 96 communicating into an annular groove 97 on the switch side of the adapter block to receive oil from the switch side of the adapter, there being a third bore 98 extending from eccentric bore 96 into a larger threaded bore 99 in the side of the block and which receives a threaded coupling nipple 100 on hose 101, the opposite end of which hose connects through nipple 102 (Fig. 3) with the solenoid valve means. The connecting hose 101 is seen in part in Fig. 1, leading from the adapter 90 up under the solenoid valve means of the control head.

As seen in Fig. 2, the solenoid valve means includes a pair of electromagnetic solenoids, 105, 106, each housed in a weatherproof casing 105a, 106a, respectively (see also Fig. 4) and both fixed on a mounting block 107 held by bolts 108 on an integral flange portion 109 of the control head casting.

Electrical connection terminals 105b, 105c for solenoid 105 are seen at the outer end of the latter in Fig. 6, identical terminals 106b, 106c being provided on solenoid 106, only terminal 106b for the latter, being visible in the views, as in Fig. 4. An outer cover plate 110, Figs. 2 and 4 is held on the outer extremities of the pair of solenoids by screws 111 threaded into the heel slugs 112 of the solenoids (see also Fig. 6).

As seen in Figs. 1, 2, and 3, the solenoid cover plate 110 is provided with a flare 113 bored to communicate interiorly of the cover plate (Fig. 3), and into which fits one end of a short conductor tube 114, the opposite end of which is seated in a bore in the block 107 communicating into the chamber 115 in a boss 115a on the governor head casting, and chamber 115 in turn communicates through a bore 116 into the switch

housing 70 (Fig. 3). Thus, electrical connections (not shown) may be passed from the switch means 81, 82 into chamber 115 via bore 116 for engagement with certain electrical terminals 118 of a weatherproof connector 119 formed to provide a cover plate for the chamber 115 and having a threaded nipple portion 120 onto which the companion coupling member (not shown) of a standard type connecting cable is threaded. Similarly, electrical conductors from the several solenoid terminals 105b, 105c, 106b, 106c (not shown), are passed from interiorly of the solenoid cover plate 110 through tube 114 and into chamber 115 for connection with certain terminals 118, and also via bore 116 for connection with certain terminals of the switch means 81, 82; electrical connections in all but the appended circuit diagram, being omitted for clarity.

Each of the solenoids has a plunger 105d and 106d, respectively (Fig. 4), to the inner ends of which are secured cross bars or yokes 105e and 106e, respectively, the typical construction being shown for solenoid 105 in Fig. 6, these yokes being accommodated in cut out portions of the solenoid mounting block 107. Attached by screws 122 to the ends of the yoke 105e in the typical construction of Fig. 6, are the stems of upper and lower poppets 123, 124, controlling the oil flow for compressing the speeder spring. Identical poppets 125 (Fig. 4) and 126 (Fig. 5) are attached to the yoke 106e of solenoid 106, the two yokes with corresponding solenoid plungers and poppet attaching screws 122 being seen also in the vertical section of Fig. 7.

Each of the four poppets aforesaid is normally seated by a spring 127 expanding between the poppet and a corresponding sealing plug 128 through which the poppet stem works; these springs also withdrawing corresponding solenoid plungers so long as the poppets remain seated.

Referring to Fig. 7, the oil supply hose 101 is connected by nipple 102 into block 107 and communicates with a bore 130 into which communicate upper and lower bores 131, 132 (Fig. 3 also); as in Fig. 4, upper bore 131 in turn communicates with a transverse bore 133 leading into the chamber behind upper poppet 123, there being an outlet bore 134 (Figs. 4 and 6) into the upper chamber B for the control piston. Thus, if solenoid core 105d be attracted, poppet 123 will open and oil from the hose connection bore 130 (Fig. 4) will pass into bore 131, transverse bore 133, past the unseated poppet and out through bore 134 into chamber B, thereby causing control piston 50 to be displaced downwardly with a consequent compression of the speeder spring 18.

Oil from lower chamber B' escapes via bore 135 (Fig. 5) around the now open poppet 124, through a vertical outlet bore 136 and thence down into the chamber 30 in the base portion of the control head casting, this exhaust oil finding its way into the drain oil chamber (not seen) of the governor.

Relaxation of the speeder spring is effected by energizing solenoid 106, so that oil from the hose connection bore 130 (Fig. 5) is admitted through the bore 132, transverse bore 133 in behind the poppet 126, past the latter and through the outlet bore 139 into chamber B' to displace the control piston 50 upwardly, oil from upper chamber B escaping (Fig. 4) through bore 140 in behind poppet 125, now open, past the poppet and through exhaust bore 141 down into chamber 30 for dumping into the governor head and return 75 in the latter to the oil drain chamber thereof.

Circuit connections for selective energization of the control solenoids are shown in Fig. 9, wherein there is provided a control switch 150 on the cockpit control panel; turning this switch lever to "Increase R. P. M." position causes it to close circuit with contact 151, thereby completing circuit from one terminal of battery 153 via conductors 154, said switch lever and contact 150, 151, and connecting cable conductor 155, contacts 118a of the cable connector, conductor 156, limit switch arm 82A, limit switch contact 158, to one terminal of solenoid 105, the remaining terminal of which is connected to a common return conductor 159, thence through cable coupling contacts 118d, cable conductor 160 to battery 153, which completes the energizing circuit for solenoid 105, and will result in a downward displacement of the control piston 50 to compress the speeder spring, which in turn will decrease the propeller pitch in known manner, and thereby cause an increase in engine speed.

If cockpit control switch 150 is held closed on contact 151 as aforesaid, piston 50 will reach the limit of downward displacement, so that switch operating washer 84 (Fig. 10) atop piston rod 32 will engage limit switch operating button 83', actuating switch 82, and thereby causing switch arm 82A to break circuit with contact 158 and thus cutting solenoid 105 out of circuit for the time being, and further causing contact 82A to close circuit with its limit switch contact 161, so that a circuit is now completed from battery or power source 153 through conductor 154, control switch arm 150, contact 151, conductor 155, coupling contacts 118a, conductor 156, limit switch arm 82A, limit contact 161, conductor 162, coupling contacts 118b, conductor 163 through limit signal lamp 164, conductor 165 back to battery or power source 153, thus lighting the limit signal lamp 164 to apprise the pilot or engineer that the propeller is set at its least pitch and no further adjustment can be made in that direction.

Similarly, if the cockpit control switch lever 150 is held closed against the "Decrease R. P. M." contact 170, power is connected from battery 153, through conductor 154, control switch arm 150 closed with contact 170, cable conductor 171, cable coupling contacts 118c, conductor 172, limit switch contact arm 81a conductor 173 to one terminal of solenoid 106, energizing the latter via return circuit 159, 118d, 160, to the remaining terminal of battery or power source 153, thus causing the control piston 50 to be displaced upwardly with a consequent relaxation of the speeder spring and increase in propeller pitch and corresponding decrease in engine speed. If the piston 50 is allowed to travel to the limit of its movement in this direction, limit switch button 83, Fig. 10, will be engaged by operating washer 84, actuating switch 81 to cause its contact arm 81a to break circuit with solenoid lead 173, and to close circuit with limit contact 175, thereby cutting solenoid 106 out of circuit for the time being, and energizing the limit signal means or lamp 164 via the circuit from battery 153, through control switch contacts 150, 170, as just described, returning through limit switch contacts 81a, 175, conductor 162, coupling contacts 118b, cable conductor 163, lamp 164, conductor 165 returning to battery 153, thereby apprising the pilot or engineer that the limit of adjustment in this direction has been reached.

Summary of operation

The complete governor control head, as illus-

trated in Fig. 1, is mounted on the aircraft engine close behind the propeller to be controlled, certain electrical cable connection being made with the cut-out switch unit 93, and an oil line connection being made for the propeller oil with the swivel fitting SF, all in accordance with known practices in connection with this type of governor, it being understood that the control head 11, mounted on the top flange 14 of the governor head, replaces other types of control, manual or electrical.

The adapter 90 (Figs. 8 and 1) is interposed between the standard cut-out switch unit 93 and its mounting flange 94 on the governor head, and oil line or hose 101 from this adapter is connected by nipple 102 (as in Fig. 3) to the mounting base 107 of the solenoid unit for delivery of engine oil to the flow control poppets 123, 126. The electrical control cable from the cockpit being connected or coupled with nipple 120, the device is in condition for operation, assuming the aircraft engine to be operating so that there will be pressure behind the engine oil adequate to actuate the control pistons or hydraulic means.

Referring to the circuit of Fig. 9, turning of switch arm 150 to contact 151 causes energization of solenoid 105 via circuit connections heretofore described in detail, it being assumed that the control piston is not at this time in one of its opposite limit positions, but is in some intermediate position (as in Figs. 3 and 10, the latter showing only the upper extremity of the piston rod 32).

As in Fig. 6, energization of solenoid 105 attracts armature plunger 105d, shifting the yoke bar 105e to the right and withdrawing both poppets 123 and 124 from their seats against the tension of their respective seating springs 127.

Raising of said poppets 123 and 124 permits oil from the engine oil supply hose 101 and solenoid base block bore 130 (Fig. 7) to pass through bores 131, 133 (Fig. 4) in behind and thence around poppet 123 and out bore 134 into control piston chamber B, thus driving the control piston 50 downwardly and thereby tensioning the speeder spring 18, (Fig. 3), the oil in lower control chamber B' at this time being expelled from said chamber through bore 135 (Fig. 5) in behind and around poppet 124, at this time open, and downwardly out bore 136 (Figs. 5 and 6) to be dumped into the space surrounding the speeder spring mechanism, from which area the expelled or exhausted oil finds its way into the governor head drain (not seen). Tensioning or compressing of the speeder spring as aforesaid decreases the pitch of the propeller through the agency of high pressure oil delivered from the governor head swivel fitting SF to the propeller hub under control of the unshown pilot valve in the governor head, which is controlled in turn by the position of shaft 20.

If the cockpit control switch arm 150 is held on contact 151 long enough to permit the control piston to reach the end of its downward travel, switch operating washer 84 (Figs. 3 and 10) will engage switch button 83' and thereby operate switch 82 to cut the solenoid 105 out of circuit and light the limit signal lamp 164 (Fig. 9).

If the cockpit control switch 150 is turned onto contact 170, solenoid 106 is energized, thereby raising poppets 125 and 126 (Figs. 4 and 5), so that oil from base block bore 130 (Figs. 7 and 5) and bores 132, 138 passes in behind and around raised poppet 126 and through bore 139 into

chamber B' of the control piston cylinder, thus displacing piston 50 upwardly and relaxing the speeder spring 43 (Fig. 3), oil from the upper chamber B being expelled through bore 140 behind and around open poppet 125 and out bore 141 (Fig. 4) to be dumped into the space about the speeder spring assembly to return to the governor head oil drain.

If the control piston is permitted to reach the end of its upward travel, as aforesaid, switch operating washer 84 will rise into engagement with limit switch operating button 83 (Figs. 3 and 10) and actuate the upper limit switch 81 to cut solenoid 106 out of circuit and to light the limit signal lamp 164 (Fig. 9) in accordance with detailed circuit connections heretofore described.

During the aforesaid upward and downward displacements of the control piston 50, regulating piston 60 moves correspondingly and displaces a captive speed controlling or regulating fluid, contained in chambers A and A', from one to the other of said chambers through orifice 66, thereby regulating the speed of said displacement of control piston 50, the regulated speed being selectively determined by the size of orifice 66 and the viscosity of the captive speed controlling fluid, said viscosity also being selected for an optimum flow rate under opposite extremes of temperature, said viscosity in general being quite low.

It is important to observe that the disclosed structure, embodying as it does twin control valves for each direction of displacement of the unitary control piston, makes possible a locking of the said piston in whatever position it is set, since the fluid displacement in the opposite chambers B and B' is at all times proportionately inverse, and piston 50 cannot move under extraneous influence so long as the poppets remain seated, but is in effect hydraulically locked in position.

The stated and inherent advantages and objects of the invention may be realized in modified forms of the specific form of the device set forth in detail herein for purposes of disclosure to the public in Letters Patent, and no limitations are thereby intended excepting as may be expressly provided by the appended claims.

I claim:

1. Hydraulic control means for use with aircraft propeller-pitch governors of the type having a speeder spring, said means comprising: a control head adapted to be mounted on a said governor and including a cylinder and a control piston reciprocable therein, speeder-spring engaging means moved by said piston in its opposite motions and projecting for engagement with a speeder spring when the control head is mounted on the governor head for compressing and relaxing said speeder spring, a first set of poppets yieldingly seated and one each of the same communicating to a different side of said control piston, means directing hydraulic displacement fluid to a first one of said poppets of the first set for admission of fluid to said cylinder to move the control piston in a first direction, the second poppet of the first said set, when open, permitting escape of hydraulic fluid from said cylinder from the side of the control piston opposite from that to which said fluid is admitted by said first poppet of the first set; a second set of poppets yieldingly seated and a first poppet of the second set, when open, admitting hydraulic displacement fluid to a side of the control piston opposite to that to which said fluid is admitted by the said first poppet of said first set, the second pop-

pet of the second set, when open, permitting escape of fluid from the side of the control piston opposite that to which said displacement fluid is admitted by said first poppet of said second set; means carried on said head and operable for opening either set of poppets at will; means directing hydraulic displacement fluid to the first poppet of the second set, said fluid normally retained on opposite sides of the control piston when said poppets are all closed and seated, whereby said control piston is hydraulically locked in position to maintain said speeder spring engaging means in a desired condition of compression or relaxation.

15 2. For use with an aircraft governor head of the type including a connection with a source of engine oil under pressure and a cut-out switch device in operative communication with said source, improvements comprising, to wit: a control head adapted to be mounted on said governor head, hydraulic means in said control head for actuating a controlled instrumentality in said governor head, said hydraulic means operated by said engine oil, valve means controlling flow 20 of said engine oil relative to said hydraulic means, and means for deriving engine oil from the governor head for operation of the hydraulic means as aforesaid, said last-mentioned means including an adapter arranged and constructed 25 to be interposed between said cut-out switch device and said engine oil source and leading off engine oil to said valve means.

3. Hydraulic control apparatus comprising two pistons on a common rod and working in a common cylinder sealed at both ends with a sealing plate between said pistons and affording, 30 hydraulic chambers on opposite sides of both pistons, an outer said piston constituting a regulating piston having a fluid escape orifice there-through, a second outer one of said pistons constituting a working piston, a captive regulating fluid in the flanking chambers of said regulating piston, an inlet duct in said cylinder communicating with each side of said working piston, an outlet duct in said cylinder communicating with each side of said working piston, poppets regulating fluid flow in said ducts, and control means including mechanism normally closing all 35 said poppets and acting to move said poppets selectively in pairs each consisting of one inlet duct on a given side of the working piston and one outlet duct on the correspondingly opposite side of said working piston, whereby the latter may be reversely displaced at a regulated rate 40 by selective opening of either pair of said poppets and hydraulically locked in any position by normal closure of all said poppets as aforesaid.

4. Hydraulic control apparatus for use with an 45 aircraft propeller governor including a speeder spring, said apparatus comprising: a single cylinder head adapted to be mounted on said governor opposite said speeder spring, a pair of co-reciprocable pistons in said cylinder and means 50 reciprocable thereby and adapted to be operatively interconnected with said speeder spring for tensioning and relaxing the latter responsive to opposite movements of said pistons, two sets of solenoid-operated dual valve means mounted on 55 said head for controlling flow of hydraulic displacement fluid selectively to and from opposite sides of one of said pistons constituting the control piston to effect selective reciprocation thereof, said other piston working against a captive fluid in 60 said cylinder sealed off from said first piston,

orifice means in said second piston permitting regulated escape of said captive fluid past said second piston in opposite movements thereof to regulate the displacement speed of said pistons under controlled hydraulic flow as aforesaid, said valve means being normally closed to trap said displacement fluid on both sides of said control piston to lock the latter in all positions, and means providing a stationary insert seal in said cylinder segregating said captive fluid from said control piston.

5. Apparatus of the class described comprising a closed cylinder, two pistons working in said cylinder on a common rod but separated by an insert sealing plate and all jointly dividing said cylinder into four chambers, one of said pistons having an escape orifice for passage of speed-regulating fluid from one to another side thereof, cylinder ducts in pairs each pair interconnecting respectively opposite sides of a second one of said pistons, a pair of poppets for each said pair of ducts, and means for simultaneously opening one, and closing one of the poppets of each said pair, whereby to admit a fluid-pressure medium selectively to either side of said second piston for effecting reverse displacements thereof, and means for connecting a source of fluid-pressure medium to said pairs of poppets, together with cylinder duct means connecting with said pairs of ducts for dumping expelled fluid-pressure medium from the chambers on opposite side of said second piston to the exterior of said cylinder through any of said poppets which are opened as aforesaid.

6. A fluid-operated servomotor comprising two pistons on a common drive rod and working in a single closed cylinder having a removable insert-sealing plate between said pistons and co-operable with the latter to define four chambers, a pair of ducts connecting opposite sides of an outer one of said pistons, constituting a working piston, through a first pair of spring-seated poppets to a fluid pressure line and an exhaust port, respectively, a second pair of ducts respectively connecting opposite sides of said working piston in a reverse sense from the first said pair with said line and an exhaust port through a second pair of spring-seated poppets, a trapped speed-regulating fluid in the chambers flanking another outer one of said pistons, said last piston having an escape orifice therethrough, and means for selectively seating and unseating either pair of said poppets to effect reverse displacements of said working piston and to hold said piston in any displaced position in normally seated condition of the poppets.

7. A fluid-operated servomotor comprising a closed cylinder, a pair of pistons spaced apart on a common drive rod therein, fluid supply inlet ducts connecting to opposite sides of a working one of said pistons, a separate poppet closing the supply duct to each said side, a cylinder exhaust duct for effluent fluid from each said side, a separate poppet closing each said exhaust duct, mechanism for simultaneously opening and closing said poppets in pairs each pair consisting of one poppet for said supply duct and one poppet for said exhaust duct, whereby said working piston may be reversely displaced and be hydraulically locked in position by fluid trapped on opposite sides of said working piston as a result of closure of all said poppets.

8. A fluid-operated servomotor comprising a head having a base constituting a cylinder closed at one end of the head and opening through into a base

10

cavity in opposite end of the head, a fluid seal between said cylinder and cavity, a piston rod working in said cylinder through said seal and piston means consisting of two pistons spaced apart on said rod in said cylinder, one piston having fluid escape passage therest, a speed-regulating fluid transferred from one to another side of said one piston responsive to reciprocation thereof, two sets of fluid inlet and exhaust ducts the ducts of each set communicating from a fluid supply connection in said head in relatively reverse relation to opposite working sides of the remaining piston, twin sets of linked poppets for each said set of ducts, and solenoid means carried on said head and selectively actuating said poppet sets to unseat the latter, from a normally seated condition, in pairs each consisting of one inlet and one exhaust poppet whereby to displace said piston assembly selectively in reverse directions by fluid from said supply, said exhaust ducts dumping into said cavity, and said piston communicating into said cavity for operative connection with a load.

9. A servo-motor for attachment as a control head on a governor head, and comprising, to wit: a body including a cylinder adapted for mounting on a governor head; two spaced pistons working on a common rod in said cylinder, the latter being closed at both ends and having an intermediate sealing portion between said pistons

30 whereby said cylinder is divided into four chambers one of which is situated on a side of each piston such that each piston is flanked by a sealed chamber, a speed-regulating orifice by-passing a first one of said pistons to interconnect the flanking chambers therefor, a speed-regulating fluid trapped on said flanking chambers, a main intake for fluid under pressure to a body portion of said cylinder, an inlet duct in said body leading from said intake into said cylinder to each side of the second and working one of said pistons, an exhaust duct in said body leading from each side of said working piston to discharge into said governor head, poppets normally seated to close all of said ducts, a pair of solenoids carried on said body and each energizable to selectively open a pair of said poppets, each said pair consisting of one inlet and one exhaust poppet for the corresponding ducts, such that energization of either solenoid will admit said fluid under pressure to one or the other side of said working piston to displace the latter oppositely under control of said regulating fluid, said piston rod being adapted for connection with governor means actuated thereby in said governor head.

55 10. The construction set forth in claim 9 further characterized by the addition of a switch chamber on said cylinder in alignment with the axis of said piston rod, a limit switch in said switch chamber and including actuating means engaged by means on said piston rod in a certain position of displacement for control of a limit signaling circuit, and means on said body affording circuit connections with said solenoids and said limit switch.

EDWARD J. COLLINS.
